United States Patent Office

Des. 200,972
Patented Apr. 27, 1965

200,972

LIGHTER

Zenzaburo Yoshino, 7-1 1-chome, Toshin-cho,
Itabashi-ku, Tokyo, Japan

Filed July 12, 1963, Ser. No. 75,764

Claims priority, application Japan, Mar. 23, 1963,
38/6,891

Term of patent 14 years

(Cl. D48—27)

Fig. 1.

Fig. 5.

Fig. 6.

Fig. 2.

Fig. 3.

Fig. 4.

FIG. 1 is a perspective view of a lighter showing my new design;

FIG. 2 is a side elevation thereof;

FIG. 3 is a top plan view thereof;

FIG. 4 is a bottom plan view thereof;

FIG. 5 is an elevation as seen from the left of FIG. 1; and

FIG. 6 is an elevation as seen from the right of FIG. 1.

The side not shown has substantially the same appearance as the side shown.

The dominant features of my design reside in the portions shown in full lines.

I claim:

The ornamental design for a lighter, substantially as shown and described.
